SILENCING MEANS FOR FLUSHING RIMS

Carl J. Kohler and Gordon P. Gavin, Kohler, Wis.

Application September 13, 1933, Serial No. 689,294

10 Claims. (Cl. 4—9)

Our invention relates to improvements in flushing rims for water closet bowls and the like, and the object of our invention is to provide means for silencing the operation of said flushing rims without seriously impairing the efficiency thereof.

We attain this object by the means illustrated in the accompanying drawing, in which Figure 1 is a side view, partly in section, of a water closet bowl embodying our invention; Fig. 2, a sectional view of a flushing rim embodying one form of the invention; and Figs. 3 and 4, respectively, a sectional view along the lines 3—3 of Fig. 4 and a bottom view of a flushing rim, 15 showing a modified form of the invention.

In the drawing the numeral 1 indicates a water closet bowl provided with the flushing rim 2, having a hollowed-out portion or channel 3, 20 which has communication at 9 with the reservoir 10 or source of water supply to the bowl. The lower portion of the flushing rim is provided, at suitably spaced intervals, with a plurality of rim flush holes 4, providing communication between the channel 3 and the interior of the 25 bowl and through which water is discharged upon the flushing of the bowl, thus cleansing the sides of the bowl. It will be seen that the rim 2 is thus enclosed and has communication with the exterior atmosphere only through the 30 communicating passageway 9 and the rim flush holes 4.

The structure thus far described is a conventional one and, as is well known, the flushing of this type of water closet bowl is ordinarily 35 attended with considerable noise which, for obvious reasons, is highly objectionable. We have discovered that a large portion of this noise is caused by the operation of the flushing rim in the following manner.

Upon flushing the bowl water is admitted to the flushing rim 2 and, in order to obtain a sufficient velocity of discharge from the rim flush holes 4 to insure adequate cleansing of the bowl, it is necessary that the channel 3 be entirely filled 45 with water. The water entering the channel 3 naturally fills the lower part of the channel first, as shown in Fig. 2, sealing the rim flush holes 4 and entrapping the air with which the channel 3 is filled in the upper portion of the channel. 50 As the channel 3 continues to fill with water, this entrapped air must be displaced, and having no means of access to the exterior atmosphere, must be forced out through the water which causes a clearly noticeable whistling noise.

Our improvement consists in providing an air

vent whereby the air contained in the channel 3 may have easy access to the exterior atmosphere so that it is not necessary that this air be forced through the water, thus materially silencing the operation of the flushing rim.

One embodiment of the improvement is illustrated in Fig. 2. In this embodiment one or more of the rim flush holes 4 is provided with a silencer tube or vent tube 5 extending therethrough to the upper portion of the channel 3. 65 The silencer tube is preferably a metal tube shaped to correspond to the shape of the rim flush hole 4. It is preferably of such size as to be slightly compressed upon insertion into the rim flush hole 4 so that its own elasticity 70 holds it in place or it may be, if desired, cemented or otherwise held in place. The silencer tube 5 acts as an air vent and allows the air to escape from the upper portion of the channel 3 through the silencer tube 5 as shown by the arrow in 75 Fig. 2. When the channel 3 completely fills, water is discharged through the silencer tube 5 in the same manner as through the rim flush holes 4. Thus the efficiency of the flushing rim is not materially impaired. Since the silencer 80 tube 5 may be inserted after the manufacture of the bowl is completed and requires no changes in the structure of the bowl, this method is adaptable for silencing water closet bowls now in use as well as those which may be manufactured 85 hereafter.

The modification illustrated in Figs. 3 and 4 illustrates one method by which the improvement may be incorporated in the flushing rim during the manufacture thereof. In this embodiment 90 the flushing rim is provided at 6 with the dam 7 which extends upwardly into the channel 3. Although, as shown, the dam 7 extends to the top of the channel 3 and bifurcates it, the specific form of the dam 7 is capable of great modification and it need not necessarily extend completely to the top of the channel 3. The dam 7 is provided with the vent passageways 8 providing communication between the channel 3 and the exterior atmosphere and providing a vent 100 for the air as indicated by the arrow in Fig. 3.

It will be understood that we do not limit ourselves to the specific structures illustrated and described, but claim all modifications thereof within the spirit of our invention and the scope 105 of the appended claims.

We claim:

1. In combination in a water closet bowl, a flushing rim having a channel therein, means for providing communication between said channel 110

and a water supply, a plurality of rim flush holes in the lower portion of said flushing rim and a silencer tube extending through one of said rim flush holes into said channel, said channel being enclosed and having communication with the exterior atmosphere only through said communicating means, said rim flush holes and said silencer tube.

2. In combination in a water closet bowl, a flushing rim having a channel therein, means for providing communication between said channel and a water supply, a plurality of rim flush holes in the lower portion of said flushing rim and a silencer tube extending through one of said rim flush holes to a point in the upper portion of said channel, said channel being enclosed and having communication with the exterior atmosphere only through said communicating means, said rim flush holes and said silencer tube.

3. In a water closet bowl, the combination of a flushing rim, a channel in said flushing rim, means for providing communication between said channel and a water supply, said flushing rim being provided with a plurality of rim flush holes extending between said channel and the lower portion of said flushing rim and a silencer tube extending through one of said rim flush holes to a point in the upper portion of said channel, said channel having communication with the exterior atmosphere only through said communicating means, said rim flush holes and said silencer tube.

4. In a water closet bowl, the combination of a flushing rim, a channel in said flushing rim, means for providing communication between said channel and a water supply, a plurality of rim flush holes in said rim and a silencer tube extending through one of said rim flush holes to a point in the upper portion of said channel, said communicating means and said rim flush holes being so positioned as to be closed by the inflow of water upon the flushing of the bowl.

5. In a water closet bowl, the combination of a flushing rim, a channel therein, means for providing communication between said channel and a source of water supply, a plurality of rim flush holes extending between said channel and the lower portion of said flushing rim, said communicating means and said rim flush holes being so positioned as to be closed by water upon initiation of the flushing of the bowl, and means for venting the air thus entrapped in said channel.

6. In a water closet bowl, the combination of a flushing rim provided with a plurality of rim flush holes, a channel therein, means for providing communication between said channel and a source of water supply, said channel being completely en-

closed except for said rim flush holes and said communicating means and said rim flush holes being so positioned as to be closed by water upon initiation of the flushing of the bowl whereby the air contained in said channel is entrapped and a silencer tube adapted to provide communication between the upper portion of said channel and the exterior atmosphere whereby to allow the escape of said entrapped air.

7. In a water closet bowl of the class comprising a flushing rim provided with a plurality of rim flush holes, a channel in said flushing rim and means for providing communication between said channel and a source of water supply and wherein said channel is completely enclosed except for said communicating means and said rim flush holes whereby the air contained in said channel is entrapped by the closing of said rim flush holes and said communicating means by water upon the flushing of said water closet bowl, the combination with said flushing rim of a silencer tube extending from the bottom portion of said flushing rim to the upper portion of said channel whereby to provide a vent for said entrapped air.

8. A method of silencing water closet bowls comprising manufacturing said bowls with a flushing rim having a channel therein and provided with a plurality of rim flush holes and, after completion of said manufacture, inserting a silencer tube through one or more of said rim flush holes into the upper portion of said channel whereby to vent the upper portion of said channel.

9. A method of silencing water closet bowls comprising manufacturing said bowls with a flushing rim having a channel therein and provided with a plurality of rim flush holes and, after completion of said manufacture, inserting a metal silencer tube through one or more of said rim flush holes into the upper portion of said channel whereby to vent the upper portion of said channel.

10. A method of silencing water closet bowls comprising manufacturing said bowls with a flushing rim having a channel therein and provided with a plurality of rim flush holes and, after completion of said manufacture, inserting a silencer tube through one or more of said rim flush holes into the upper portion of said channel whereby to vent the upper portion of said channel, said silencer tube being of such size and elasticity as to be retained in position in said rim flush hole by its own elasticity.
